(57) **CLAIM**

The ornamental design for a brake caliper hardware, as shown and described.

DESCRIPTION

FIG. 1 is a front isometric view of a brake caliper hardware in accordance with the new design;
FIG. 2 is a front elevational view thereof;
FIG. 3 is a right side elevational view thereof, the left side being a mirror image thereof;
FIG. 4 is a rear elevational view thereof;
FIG. 5 is a top plan view thereof; and,
FIG. 6 is a bottom plan view thereof.

1 Claim, 6 Drawing Sheets
